STITCH-FORMING MECHANISM.

1,092,821.

Specification of Letters Patent. Patented Apr. 14, 1914.

Original application filed February 27, 1909, Serial No. 480,338. Divided and this application filed March 4, 1910. Serial No. 547,243.

To all whom it may concern:

Be it known that I, OTIS E. BROWN, a citizen of the United States, residing at Brockton, in the county of Plymouth and State of Massachusetts, have invented certain new and useful Improvements in Stitch-Forming Mechanism, of which the following is a specification, reference being had therein to the accompanying drawings.

10 This application is a division of my application, filed February 27, 1909 (Patent No. 1,002,217, dated September 5, 1911), and the present invention relates to an improvement in stitch-forming mechanism designed 15 more particularly for wax thread sewing machines, although not limited to such type of machines.

The invention has for its primary object to provide a simple and effective actuating 20 mechanism for imparting reciprocatory movements to the needle; and to this end the actuating mechanism comprises a pitman-lever connected with an actuating crank and mounted upon a movable fulcrum 25 having means for guiding it in a defined path, said pitman-lever being connected with a crank-arm upon one end of a rock-shaft whose other end is connected with the needle-bar carrying the needle. The oscillatory 30 loop-taker preferably has an operative connection with said pitman-lever whereby the loop-taker receives operative movements in harmony with those of the needle to insure their proper coöperation in the production 35 of stitches.

In the drawings, Figure 1 is a sectional rear side elevation of a machine embodying the present improvements, Fig. 2 a transverse section through the head of the 40 bracket-arm, looking forwardly, Fig. 3 a front end view representing the forward portion of the machine, and Fig. 4 an elevation representing the needle and loop-taker actuating mechanism detached from the 45 frame of the machine.

As represented in the drawings, the frame of the machine comprises the hollow standard 1 with cylindrical work-supporting arm or horn 2 and hollow overhanging bracket-arm 3 terminating in the usual head 4. The needle 5 is mounted in the reciprocating needle-bar 6 journaled in the upper and lower bearings 7 of the laterally movable needle-frame 8. The needle-bar carries the usual

collar 9 with lateral stud 10 embraced by one 55 end of the link 11 whose opposite end is connected with the stud 12 carried by the forwardly projecting crank-arm 13 of the needle-actuating rock-shaft 14 mounted in suitable bearings upon and longitudinally 60 of the overhanging bracket-arm 3. At its rearward end, the rock-shaft 14 is provided with a depending crank-arm 15 connected by means of a link 16 to the upper end of a link-bar 17 whose lower end is provided with 65 a strap 18 embracing the actuating crank 19 formed in the driving shaft 20 which is journaled within and transversely of the standard 1 parallel with the needle-actuating rock-shaft 14. As represented in the 70 drawings, the rock-shaft 14 extends entirely across the upper end of the hollow standard 1 and has its rearward bearing at its extreme rearward end adjacent the crank-arm 15.

75 Loosely mounted upon a shaft 21 journaled upon center screws 22 in the bearing lugs 23 extending rearwardly from the standard 1 is a sleeve 24 confined between thrust-collars 26 and constituting a member 80 of a swinging yoke 27 which carries the conical center screws 28 entering the similarly apertured bosses 29 extending from the opposite faces of the link-bar 17. In following the rotary movements of the actuating crank 19 of the driving shaft, the link-bar 17 is thus adapted to move bodily upon the axis of oscillation of the yoke or radius-bar 27, whereby the upper end of the link-bar 17 connected with the link 16 is moved 90 in a substantially elliptical path with a nearly vertical major axis adjacent the rock-shaft 14, and is confined to a range of movement permanently at one side of the axis of oscillation of the needle-actuating rock-shaft. 95

The several members of the mechanism are so proportioned and arranged that when the upper end of the link-bar is rising from its extreme lower and rearward position, a 100 little below the position indicated in dotted lines in Fig. 4, its relation to the depending arm 15 of the rock-shaft is such that the needle is in its lowest position. As the link-bar rises to and slightly above the dotted-line position of Fig. 4, the arm 15 is swung 105 slightly forwardly to raise the needle sufficiently to throw out its loop for the shut-

tle, after which it moves upwardly and forwardly practically in an arc described by the link 16, whereby the arm 15 is maintained stationary for a time sufficient to permit the distention of the needle-thread loop by the shuttle and the advance of the material under the feeding action, after which the approach of the upper end of the link-bar to the rock-shaft and its continued movement beneath the same causes the rapid movement of the crank-arm 15 to extreme forward position and consequent rise of the needle to its highest position. In the descent and backward movement of the upper end of the link-bar 17, the latter reaches its most advantageous relation with the crank-arm 15 just as the needle is entering the goods resting upon the throat-plate 2^x for a succeeding stitch, thus insuring the application of the full force of the mechanism at the time when the greatest load is imposed thereon.

The lower portion of the link-bar 17 is provided adjacent the strap 18 with a rearward offset or extension 17^x carrying a stud-screw 30 embraced by one end of a pitman 31 whose opposite end embraces a similar stud-screw 32 carried by a lateral crank-arm 33 of a rocking sleeve 34 which is provided with a forked arm 35 which embraces a roller-stud 36 carried by a crank-arm 37 upon the rearward end of the shuttle actuating rock-shaft 38 which is journaled in bearings 39 within the cylinder arm 2 and carries at its forward end the shuttle-driver 40. The shuttle 41 is of the wellknown Singer oscillating type, provided with the barrel thread-case 42 and fitted to oscillate within a race 43 at the forward end of the cylinder-arm 2, the throat 44 and heel 45 of the shuttle being alternately engaged by the arms of the shuttle-driver in a well-known manner. By the particular arrangement of the link connection 31 with the link-bar 17 described above, the shuttle movements, are timed, as before recited, so as to coöperate with the needle in the manipulation of the upper thread so as to seize and distend the needle-thread loops while the needle-eye is beneath the work, thus avoiding any undue strain upon the thread in the loop-seizing and casting operations which would be produced in case the rise of the needle were hastened or the action of the shuttle upon the needle-thread were delayed.

Mounted loosely upon the rock-shaft 14 between the thrust-collars 46 is a rocking sleeve 47 having two rearwardly projecting and angularly disposed arms 48 and 49, the former of which is connected by means of the link 50 with the upper end of the link-bar 17 by means of the stud-screw 51 to which the link 16 is connected. The crank-arm 49 of the sleeve 47 is connected by

means of a bent link 52 with a crank-arm 53 fixed upon the take-up rock-shaft 54 mounted in suitable bearings 55 upon the bracket-arm 3. The rock-shaft 54 is provided intermediate said bearings with an offset portion 56 between which and its extreme forward end it is formed with an axial thread-aperture 57.

Upon the forward end of the rock-shaft 54 is fixed the hub 58 of the take-up arm or lever 59 carrying the grooved tension-wheel 60 one side of which is disposed substantially in alinement with the thread aperture of the take-up rock-shaft, the tension-wheel being journaled upon the pin 61 fitted to a suitable transverse bearing of the take-up arm and having a head 62 normally resting upon the outer face of the take-up wheel, a spring 63 being interposed between the bearing in the arm 59 and the adjusting nut 64 applied to the threaded opposite end of the bearing pin, whereby the tension-wheel 60 is normally subjected to a slight frictional drag which is increased at such times as the vibration of the take-up arm carries the head 62 of the bearing pin 61 into engagement with the spring-arm 65 secured upon the split supporting pin 66 mounted in the bracket-arm.

The take-up arm 59 carries at its outer end the thread wheel 67 mounted upon the stud-screw 68 and intermediate its ends a similarly grooved thread-wheel 69 mounted upon the stud-screw 70, each of said thread-wheels being embraced between the expanded adjacent ends of the guard-loops 71 and 72 respectively. Mounted upon the fixed supporting member 73 carried by the head of the bracket-arm is the screw-stud 74 which is provided in practice with a grooved thread-wheel embraced by the enlarged extremity of a guard-loop 75 extending backwardly therefrom.

In the use of the machine the thread is led from the source of supply through the longitudinally apertured forward portion of the take-up rock-shaft 54, around the tension-wheel 60, thence beneath a guide-roll 76 upon the take-up arm and between guide-rolls mounted upon stud-screws 77 in the bracket-piece 78 secured to the needle-frame 8 by the fastening screw 79, and thence through the guide-strap 80 to the eye of the needle 5. Between the guide-roll 76 and the stud-screws 77 the thread is confined against disarrangement by passing through the guard-loops 71, 75 and 72.

The take-up arm assumes its lowest position just after the point of the shuttle has seized the needle-thread loop, and starts its rising movement without any immediate effect upon the thread extending from the roll 76 to the guiding stud-screws 77 until the shuttle has reached its most advanced position and the eye of the needle has risen

above the work, when the grooved rollers 67 and 69 engage the thread below and upon opposite sides of the stationary guide-roller supporting pin 74, and the continued rise 5 of the take-up arm causes the bending of the thread around the stationary roller for taking up the slack needle-thread and setting the stitch, the latter being effected as the take-up arm and the needle reach their highest 10 positions. As the take-up arm descends, slack needle-thread is given up to permit the seizure and expansion of the needle-thread loop by the shuttle for the succeeding stitch.

The driving shaft is provided, adjacent 15 the crank 19, with a feed-actuating cam 81, which is embraced by a yoke 82 formed at the lower end of a rock-lever 83 whose upper end is pivotally connected by means of the screw-stud 84 with the depending crank-arm 20 85 at the rearward end of a rock-shaft 86 mounted upon the front side of the bracket-arm 3 and having fixed upon its forward end a depending arm or lever 87. The arm 87 is pivotally connected by means of a pin 88 25 with a forwardly extending lug 89 of the needle-frame 8 whose rearward edge has a lug 90 carrying a stud 91 sustaining a slide-block 92 which moves in the stationary segmental slideway 93 having a curvature corresponding 30 with the path of circular movement of the pivotal pin 88 by which the opposite edge of the needle-frame is supported, to insure the parallelism of the needle-frame in the different lateral positions which it assumes under the action of the feed-cam 81.

The stitch-regulating lever 94 has one end integral with the rock-shaft 21 and its other end projects forwardly therefrom, while its 40 intermediate portion carries the fulcrum-stud 95 entering a segmental recess 96 of the lever 83 for which it affords a movable fulcrum. The position of the lever 94 obviously determines the fulcrum point of the rock-lever 83 by means of which the range of 45 lateral movement of the needle in the line of seam is determined.

The feed-actuating cam 81 is so shaped and secured upon its supporting shaft that it 50 imparts to the needle, through the described connections, a lateral feeding movement during the dwell of the needle in each reciprocation and while the needle-thread loop is being distended and cast about the lower 55 thread by the shuttle. This relative timing of the needle and shuttle actuations is important, because the advance of the work should be delayed until the seizure of the needle-thread loop by the shuttle to insure 60 certainty of action of the latter, and should terminate before the point of the needle emerges from the work so as to utilize each entire feeding movement of the needle without injury to the face of the work by the 65 emerging point of the needle. The needle re-

ciprocating mechanism herein shown and described is particularly adapted to produce a dwell of the vertical movement of the needle at such time and of such duration as to coöperate with the shuttle mechanism and 70 the feeding means to accomplish the described result.

Having thus set forth the nature of the invention, what I claim herein is:—

1. In a sewing machine, the combination 75 with a driving shaft a throat-plate, an endwise- and sidewise movable eyed needle, and a loop-taker coöperating with said needle in the production of stitches, of actuating means connected with the driving shaft for imparting to the needle endwise reciprocating movements with a dwell while the needle is between extreme positions and while the needle-eye is at that side of the throat-plate adjacent the loop-taker, means operatively 80 connected with said needle-actuating means for actuating the loop-taker to seize and distend a needle-thread loop before the end of the dwell of said needle, and means for imparting to the needle sidewise work-feeding 85 movements during said dwell in its reciprocatory movements.

2. In a sewing machine, the combination 90 with the main-shaft provided with a crank, of a pitman-lever connected with said crank, 95 a movable fulcrum for said pitman-lever with means for guiding it in a defined path, a rock-shaft, a crank-arm thereon, a connection intermediate said crank-arm and pitman-lever, a needle-bar, a needle carried 100 thereby, an operative connection intermediate said needle-bar and rock-shaft, a loop-taker, and means connected with and actuated through said pitman-lever independently of its fulcrum-guiding means for actuating said loop-taker.

3. In a sewing machine, the combination 105 with the main-shaft provided with a crank, of a pitman-lever connected with said crank and carrying a pivotal stud offset from such 110 point of connection, a movable fulcrum for said pitman-lever with means for guiding it in a defined path, a rock-shaft, a crank-arm thereon, a connection intermediate said crank-arm and pitman-lever, a needle-bar, a needle carried thereby, an operative connection intermediate said needle-bar and rock-shaft, a loop-taker, an actuating rock-shaft for the same provided with a crank-arm carrying a stud, a plural-armed rocker having 115 one arm slotted to embrace said stud, and a connection between a second arm of said rocker and the pivotal stud upon said pitman-lever.

4. In a sewing machine, the combination 120 with the main-shaft provided with a crank, of a pitman-lever connected with said crank, a movable fulcrum for said pitman-lever with means for guiding it in a defined path, a rock-shaft, a crank-arm thereon, a second 125

- rock-shaft, a crank-arm thereon, independent connections between said pitman-lever and the crank-arm of said rock-shafts, a needle-bar, a needle carried thereby, an operative connection intermediate said needle-bar and the first-named rock-shaft, a take-up arm mounted upon the second-named rock-shaft, a loop-taker, and means for actuating said loop-taker.
10. 5. In a sewing machine, the combination with the main-shaft provided with a crank, of a pitman-lever connected with said crank, a movable fulcrum for said pitman-lever with means for guiding it in a defined path, 15 a rock-shaft, a crank-arm thereon, a second rock-shaft, a crank-arm thereon, an intermediate rocker, a pitman connection intermediate said rocker and the crank-arm of the second-named rock-shaft, independent connections 20 between said pitman-lever and the crank-arm of the first-named rock-shaft and between said pitman-lever and said intermediate rocker, a needle-bar, a needle carried thereby, an operative connection intermediate 25 said needle-bar and the first-named rock-shaft, a take-up arm mounted upon the second-named rock-shaft, a loop-taker, and means for actuating said loop-taker.
6. In a sewing machine, the combination 30 with the main-shaft provided with a crank, of a pitman-lever connected with said crank, a movable fulcrum for said pitman-lever with means for guiding it in a defined path, a needle-actuating rock-shaft, a take-up 35 rock-shaft, a crank-arm upon each of said rock-shafts, independent connections between said crank-arms and the pitman-lever, a needle-bar, a needle carried thereby, an operative connection intermediate said needle- 40 bar and needle-actuating rock-shaft, a take-up arm mounted upon the take-up rock-shaft, a loop-taker, and means for actuating said loop-taker.
7. In a sewing machine, the combination

with a driving shaft, a throat-plate, an end-wise and sidewise movable needle, and a loop-taker coöperating with said needle in the production of stitches, of actuating means operated by said shaft for imparting to the needle endwise reciprocating movements with a dwell while the needle is between extreme positions and while the needle-eye is at that side of the throat-plate adjacent the loop-taker, means having direct operative connection with said needle-actuating means, for actuating the loop-taker to seize and distend a needle-thread loop before the end of the dwell of said needle, and means for imparting to the needle sidewise work-feeding movements during said dwell in its reciprocatory movements.

8. In a sewing machine, the combination with the main-shaft, of a pitman-lever connected to said shaft, a needle, a loop-taker coöperating with said needle in the production of stitches, a take-up arm, rock-shafts and connections adapted to actuate said needle, loop-taker, and take-up arm, means for imparting to the needle sidewise work-feeding movements, and means directly connecting said rock-shafts and pitman-lever whereby the movement of the latter serves to impart to the needle endwise reciprocating movements with a dwell while the needle is between extreme positions, actuate the loop-taker to seize and distend the needle-thread loop before the end of the dwell of said needle, and impart operative movements to the take-up arm.

In testimony whereof, I have signed my name to this specification, in the presence of two subscribing witnesses.
